[57] CLAIM

The ornamental design for a desk top terminal having angularly adjustable display module, as shown and described.

DESCRIPTION

FIG. 1 is a top, front, side perspective view of a desk top terminal with an angularly adjustable display;
FIG. 2 is a top plan view thereof;
FIG. 3 is a front elevational view thereof;
FIG. 4 is a rear elevational view thereof;
FIG. 5 is a side elevational view thereof;
FIG. 6 is a side elevational view thereof opposite to that shown in FIG. 5 with the display in the retracted position;
FIG. 7 is a side elevational view thereof with the display in a fully raised position;
FIG. 8 is a bottom plan view thereof.
